HYDRAULIC GRAB BUCKET

Richard A. Wallers, Balboa Island, Calif., assignor to Calweld, Inc., Los Angeles, Calif., a corporation of California

Filed June 11, 1964, Ser. No. 375,975
10 Claims. (Cl. 175—316)

This invention relates to a grab bucket to be utilized in earth drilling operations, and more particularly relates to a grab bucket which is hydraulically actuated whereby earth, rocks or other obstructions may be gripped by jaws on the bucket and the obstructions removed from a drilling hole. The application is a continuation-in-part of my copending application, Serial No. 139,430, filed September 20, 1961, now abandoned.

Heretofore, in the construction field relating to the drilling of wide diameter bores or holes in the earth for concrete pilings, footings, etc., when a large rock or boulder was encountered in the drilling operation it was necessary to withdraw the drilling bucket or auger and insert a mechanically actuated grab bucket which had a plurality of jaws that were forced open and held in an open position by means of a spring-loaded trigger mechanism. When the grab bucket was lowered into the hole and encountered the obstacle the trigger would be tripped releasing the jaws to grab or to clamp upon the object which was obstructing the drilling operation. This spring-loaded type of mechanical grab bucket has proved to be ineffective in situations where the drilling hole or bore is filled with a drilling mud substance because as the mechanical spring-actuated grab bucket was inserted in the bore the pressure of the fluid drilling mud upon the trigger mechanism would trip the trigger and close the jaws prematurely. A slight advance over the art, but still cumbersome apparatus, is the utilization of a hydraulic system mounted upon the drilling rig with a series of hydraulic hoses extending up to a swivel mounted on a hollow kelly thence down the inside of the kelly to the grab bucket which is secured at the end of the kelly bar. The constant rotation of the kelly bar has caused the hydraulic hoses to twist the lines around the kelly bar on occasions, and also when the swivel at the top of the kelly has become rusted or will not function the hydraulic hoses would snap and they would have to be replaced. Further, this prior apparatus was limited in its use to the length of the particular kelly bar which was being used at that time by the drilling rig, whereas in the present invention the hydraulic grab bucket is a self-contained unit including a hydraulic mechanism as a part of the grab bucket and is connected to the jaw portion of the bucket, and the whole assembly may be lowered to any depth necessary to meet the obstacle to be removed, merely by using additional lengths of kellys. Further, the present invention cannot be prematurely activated by any fluid drilling mud or any other liquid substance which may be in the bore, because the jaws are not activated until the obstacle is reached.

An object of this invention is to provide a grab bucket having a plurality of pivoted jaws which may be used to grip an object impeding progress in the drilling of a hole or bore in the earth.

Another object of this invention is to provide a grab bucket having a plurality of jaws which are hydraulically actuatable to grip and release.

A further object of this invention is to provide a grab bucket having gripping jaws which are hydraulically actuated and where the hydraulic system is an integral part of the grab bucket.

Another object of this invention is to provide a grab bucket which is adapted to be used with a conventional earth drilling rig.

Another object of this invention is to provide a grab bucket which includes a hydraulic pump means and piston ram means linked to a plurality of pivoted clamping or gripping jaws.

5 The invention consists of the construction, arrangements and combination of various parts of the device wherein the objects contemplated are attained as hereinabove more fully set forth, specifically pointed out in the claims and illustrated in the accompanying drawings, in which:

10 FIGURE 1 is a side elevational view of a mobile drilling rig utilizing a hydraulic grab bucket;

FIGURE 2 is a side elevational cross sectional view of the grab bucket showing the jaws in open position;

15 FIGURE 3 is a side elevational view taken on line 3—3 of FIGURE 2;

FIGURE 4 is a cross sectional view of a portion of the grab bucket showing one of the jaws in a closed or gripping position;

20 FIGURE 5 is a cross sectional view taken on line 5—5 of FIGURE 2;

FIGURE 6 is a cross sectional view taken on line 6—6 of FIGURE 2;

25 FIGURE 7 is a schematic view showing the hydraulic system;

FIGURE 8 is a side elevational cross sectional view of a modified hydraulic grab bucket, illustrating hydraulic link arms to activate the jaws;

30 FIGURE 9 is a side elevational cross sectional view of the modified form illustrated in FIGURE 8 showing the jaws in closed position;

FIGURE 10 is a view of one of the jaws and hydraulic actuating means of the modification taken on line 10—10 of FIGURE 8;

35 FIGURE 11 is a top elevational view taken on line 11—11 of FIGURE 8; and

FIGURE 12 is a schematic view of the hydraulic system to actuate the hydraulic actuator means.

The hydraulic grab bucket generally designated 10 is 40 designed to be used in conjunction with a drilling rig generally designated 12, which rig may be of any of those of the well known kinds, such as a crane drilling attachment, auger type rigs, or, as illustrated in FIGURE 1 for purposes of illustration only, a mobile truck mounted

45 drilling rig. The rig includes a boom 14 suspended from a truck platform 16, a kelly bar 18 suspended from a swivel 20' which in turn is secured to a cable 20 which is passed over the boom 14 and is wound upon a winch 22. The kelly bar 18 extends through a rotary 24 sus-

50 pended from the rear of the truck platform 16. The kelly bar 18 is equipped with a yoke, not shown, which fits within the rotary 24 and said rotary 24 is driven from a shaft, not shown, which is connected to the motor 26. The hydraulic grab bucket 10 is suspended from the 55 end of the kelly bar 18 and lowered within a wide diameter hole or bore 28 to the object 29 which is desired to be removed.

The grab bucket 10 is generally formed of two sections, a hydraulic section generally designated 30 and a jaw 60 section generally designated 32 collectively referred to as a shell. The hydraulic section 30 includes a tubular cylindrical casing or shell 34 formed with an external annular flange 36 at the lower end of the casing 34. The flange 36 has a number of bolt openings 37 extending therethrough around the flange. The interior of the casing 34 is generally divided into three chambers, a reservoir chamber 38, a coupling chamber 40, and a hydraulic pump chamber 42. The chamber 38 is formed between a cap plate 44 welded or otherwise secured to the top of

65 the casing 34 and a similar plate 46 of smaller diameter which is welded or otherwise secured to the interior of the casing 34. Both the plates 44 and 46 are provided

70

with centrally located aligned openings and a tubular shaft housing 48 extends between the respective plates 44 and 46, and is secured to both plates. Thus the chamber 38 is actually formed by the casing 34, plates 44 and 46 and the housing 48.

The cap plate 44 has an annular ring 50 mounted on a top surface 52 and the annular ring is formed with an internal groove 54. This groove accommodates an O ring 56.

A unitary upper drive shaft assembly 58 includes a main body portion 60 which is fitted within the tubular shaft housing 48 and a bushing 62 is provided between the main body 60 and the tubular shaft housing 48. This bushing may be of bronze or any other suitable material. The upper part of the drive shaft assembly 58 is formed with a head portion 64 on the body 60 of wider diameter than the main body 60, and the head portion 64 is seated within the annular ring 50 and bears against the O ring 56 seated in the groove 54. On top of the head portion 64 there is provided a kelly drive box 66 which is adapted to receive the end of the kelly 18. The box 66 has corresponding openings 68 in opposite walls 70 and 72 of the box to receive a nut and bolt assembly 74 which extends through the openings 68 and an opening 73 in the kelly bar 18 aligned therewith.

The opposite end 71 of the body portion 60 includes an annular groove 75 and the extreme end of the shaft assembly 58 is of a reduced diameter forming a stub 76.

In assembly the shaft assembly 58 is inserted in the cylinder 48 from above the top plate 44 so that the head portion 64 rests upon a bushing 78 within the annular ring 50. The main portion 60 extends through the cylinder 48 and the end 71 extends below the plate 46. In order to hold the shaft assembly 58 in position so that it cannot pull out of the cylinder 48, a flat bushing plate 80 is fitted around the main body portion 60 against the plate 46. A washer plate 82 is then positioned over the flat bushing 80 and a split ring assembly 84 is fitted around the shaft 58 within the groove 75. The split ring 84 consists of two plates which are secured by means of bolts 86 to the washer plate 82. In this manner it will be seen that the shaft assembly 58 when placed in position cannot be withdrawn from the cylinder 48 until the split ring 84 is removed from the groove 75.

The coupling chamber is formed between the plate 46 and an annular interior flange 88 to which is bolted by means of bolts 90 a pump plate 92.

Within the coupling chamber 40 there is suspended from the stub shaft 76 a flexible coupling 94. The coupling may be any of a variety of rubber couplings commercially obtainable.

Suspended within the chamber 42, formed at its upper end by plate 92, is a hydraulic piston pump 96 which is secured to the pump plate 92 by means of a plurality of bolts 98. The shaft 100 of the pump 96 extends through the plate 92 and into the flexible coupling 94. The pump 96 may be any of a variety of hydraulic piston pumps which includes an inlet port 102 and an outlet port 104.

The jaw section 32 includes a circular plate 106 having a plurality of openings 108 extending through the plate 106 adjacent the exterior circumference of the plate. The openings 108 are aligned with the corresponding openings 37 which are formed in the annular flange 36. Sections 30 and 32 are secured together by means of bolts 112 which pass through the openings 108 and 37 and held together by means of the nuts 114 on the bolts 112. The plate 106 is provided with a hydraulic hose fitting 116 which extends through the plate 106, as best seen in FIGURES 2 and 4.

Secured to the underside of the plate 106 is an elongated tubular cylinder 118. This cylinder 118 is welded or otherwise secured to the plate 106, and is provided with three elongated slots 120. These slots are equally spaced around the perimeter of the cylinder 118. The

jaw section 32 further includes three pairs of generally triangular shaped guide members 122. These guide members 122 extend from the plate 106 down the cylinder 118 to a point near the bottom of the cylinder, and extend radially outward therefrom. Each pair of guides 122 are equally spaced around the perimeter of the cylinder 118 so that the elongated openings 120 are between the respective pairs. Further, the individual guide member 122 of each pair is parallel with the other of the pair.

Centrally located within the cylinder 118 the plate 106 is provided with a threaded boss 124 which extends downward into the cylinder 118. Threadably secured to the boss 124 is a hydraulic ram casing 126 which extends downward in the cylinder 118. The bottom of the hydraulic ram casing 126 is open and a hydraulic ram 128 is slidably mounted in the ram casing 126. Adjacent the bottom of the ram casing 126 there is provided a grooved portion which receives a sealing ring 130 to keep hydraulic fluid from flowing between the hydraulic ram and ram casing.

Positioned around the hydraulic ram casing 126 is a hollow elongated piston 132 having a closed end 134 at its base end and three ear extensions 136 extending radially outward from the cylinder through the respective slots 120 of the tubular cylinder 118.

Surrounding the piston 132 within the casing 118 is a compression spring 138 having one end abutting against the ear extensions 136 and the other end abutting against an end cap 140 which is held within the cylinder 118 by means of a plurality of bolts 142 spaced around the perimeter of the cylinder 118. The compression spring 138 will constantly urge the piston 132 upward toward the plate 106 unless the spring is overcome by hydraulic pressure to be described, in which case the piston 132 will be forced from a position as shown in FIGURE 2 to a position as seen in FIGURE 4, where the spring 138 is compressed.

A linking or actuating means between the ear extensions 136 and jaws 144 includes a link arm 146 having a bifurcated upper end or yoke 148 which receives the end of the ear extension 136. The arm extension and yoke 148 are held together by a pivot pin 150 which extends through the bifurcated portion 148 and the arm extension 136. The link arm 146 extends downward between a pair of jaw gussets 152 which are pivotally secured to the pair of guide members 122 by means of a pin 154. These gussets 152 are generally triangular shaped and are pivotally connected to the guide members 122 near an apex of the triangle. The link arm 146 is pivotally secured between the two jaw gussets 152 by means of pivot pin 156 which passes through the jaw gussets and link arm 146 adjacent the arcuate base edge 158.

Secured to the jaw gussets 152 is the jaw 144 including a support plate 145 and arcuate blade 147 secured to the plate 145.

The hydraulic system utilized in the present invention includes a hydraulic hose 160 extending from a fitting 161 in the bottom of the reservoir chamber 38 to the inlet port 102 of the pump 96. The hose 160 is provided with a four-way coupling 164 from which a hose 166 extends to a mechanically actuated valve 168 mounted in the shell or casing 34. This valve 168 is provided with a protective annular hood 170 which is secured to the shell 34. The other opening in the coupling 164 receives a hydraulic hose 172 which extends to an automatic check valve 174. From the outlet port 104 of the pump 96 a hydraulic hose 176 extends to the fitting 116 and a hose 178 is provided which extends from the other side of the fitting 116 to a fitting in the hydraulic ram casing 126, which communicates with the interior of the casing 126. Another four-way coupling 180 is provided in the hose 176 and a hose 182 extends from the check valve 174 to the coupling 180, and the other port of the coupling

180 is fitted with one end of a hose 184 which extends to the mechanically actuated valve 168.

It should also be noted that the grab bucket 10 has an opening 190, which extends through the cap 140 into the interior of the casing 118. The opening is provided so that when the grab bucket 10 is lowered into a drilling hole 28 which contains drilling fluid, water, mud, etc., the resistance of the device to the substance is lessened by allowing it to flow through the opening 190 into the casing 118 and out the slots 120 in the casing 118. In this way resistance is lessened as the bucket is lowered into the hole 28. Further, when the hydraulic section 30 is secured to jaw section 32, the interior of the casing 34 will be water tight.

In view of the fact that when drilling wide diameter holes, the diameters may and usually do vary, this invention may be used in any large diameter hole by changing only the jaws 144 to increase or decrease the size of bite to be taken by the jaws 144.

In operation, after the grab bucket 10 has been secured to the kelly bar 18 and lowered into the hole 28, it is allowed to contact the obstacle which is desired to be removed. At this point, the kelly bar 18 is rotated the desired number of revolutions by means of the rotary 24 engaging the yoke (not shown) which is secured to the kelly bar. It should be noted that the swivel 20' will keep the cable 29 from rotating with the kelly. As the kelly bar rotates, it in turn will rotate the shaft assembly 58, coupling 94 and shaft 100 of the hydraulic pump 96. As the pump 96 is rotated, hydraulic fluid 186, which has been placed in chamber 38 through an opening at the top of the chamber capped by plug 188, is forced through the hose 160 into the inlet port 102 of the pump 96, thence under pressure out the outlet pipe port 104 through the hoses 176 and 178 into the ram casing 126. As the pressure of the hydraulic fluid builds up, it will urge the ram 128 downward against the end 134 of the piston 132. In this manner the piston 132 will be forced from a closed position illustrated in FIGURE 2 to an open position illustrated in FIGURE 4. As the cylinder moves downward within the casing 118, the link arm 146 is pushed downward and the jaw gussets 152 will pivot about pin 154 causing the jaws 144 to be moved from an open or vertical position to a closed or inwardly angled position gripping the obstacle to be removed.

When the kelly bar 18 has been rotated sufficiently to build up the pressure necessary through the pump 96 to close the jaws 144, it is stopped and the jaws in the position illustrated in FIGURE 4 will remain in that position upon the obstacle to be removed until it is desired to manually open the jaws and release the gripped object.

In order to release the jaws to the position illustrated in FIGURE 2, the manually operated valve 168 which is normally in a closed position is opened so that the fluid within the ram casing 126 is allowed to flow through hose 178, 176, 184, 166 and 160, into the reservoir 38. It should be noted that the compression spring 138 will act to force the ram 128 upward into the casing 126, thus forcing the hydraulic fluid back through the valve 168 to the reservoir.

The positioning of the check valve 174 within the hydraulic system is a safety feature so that should the pressure of the hydraulic fluid coming from the pump 96 to the ram casing 126 build up to above a predetermined pressure of pounds per square inch, for which the valve 174 is set, the hydraulic fluid may be allowed to bleed back to the reservoir through hose 182, through the valve 174, hose 172 and hose 160 into the reservoir.

A modified form of hydraulic grab bucket 10' is illustrated in FIGURES 8 to 11. In this modification, the hydraulic actuator means 200 actually replace the link arm 146 and the cylinder 118. The sections 30' and 32' or shell of the bucket 10' remain in substance the same as is illustrated in FIGURES 1 through 7; however, the hydraulic system differs to some extent within the section 30' from that illustrated in FIGURE 2.

The operative parts within the section 30' include an internal gear 202 mounted on the stub 76'. A smaller gear 204 mounted on a stub shaft 206 meshes with gear 204. The shaft is journaled in bearings 208. Intermediate the bearings 208 the shaft 206 is fitted with a sprocket 210, best seen in FIGURE 11.

The rotation of the kelly 18 will rotate the sprocket 210 which by means of a sprocket chain 212 will revolve the hydraulic piston pump 96'. The pump 96' includes inlet and outlet ports 102' and 104' and an inlet pipe 160' from the reservoir 38' to the pump 96'.

The hydraulic actuator means 200 includes a pair of hydraulic rams 214 each being suspended from a pin 216 from the plate 106'. The pins 216 pass through ring extensions 218 at the closed end of casing 220. At the end remote from said closed end a plug 222 is threadably mounted in the casing. The plug has a bore 224 to receive a piston rod 226 to which is attached a piston 228.

At the other end of the rod 226 a fitting 230 is secured. The fitting includes a bore 232 through which a pin 234 extends which pivotally connects the jaw 144' and rod 226.

The jaw 144' is pivotally connected to or carried by the shell or the lower section 32' of the bucket 10' by pivot pins 154'.

The hydraulic system of the modification of FIGURE 8 differs from the embodiment of FIGURE 2. An input line 240 passes from the pump 96' to the casing 220 to allow fluid to force the piston 228 down to a position shown in FIGURE 9 to close the jaws 144'. Fluid under the piston will be forced out of outlet line 242 to an accumulator 244 of any of the pressure bladder type commercially available. The accumulator 244 will retain the fluid until the fluid entering line 240 is evacuated, either to a second accumulator 250 or to the reservoir 38'; then the pressure within the accumulator 244 will expand the bladder and force fluid into the casing to retract the piston 228.

Line 246 is a bypass line for fluid and serves to transport fluid back to the reservoir 38' through line 248 when certain preset limits be exceeded. The valve 168' serves a similar purpose as valve 168 in FIGURE 2.

It has been found that when employing the modified form of hydraulic grab bucket 10' there is less chance of mechanical failure because none of the actuating mechanism for the jaws 144' are exposed to become clogged by earth. Further, with the modified form, only two jaws are employed; therefore, the relative diameter of the bucket 10' can be reduced over the form illustrated in FIGURE 2 and as such it has a somewhat wider application of uses.

While the primary purpose of the present invention is to remove objects such as rocks, boulders, etc. from a wider diameter hole, it must be recognized that the invention may also be used to clam, loosen and remove earth from a drilling operation. When clamping the jaws 144 will be allowed to penetrate the earth, dig and then close upon the loosened earth so it may be removed from the hole.

While the instant invention has been shown and described herein in what is conceived to be the most practical and preferred embodiment, it is recognized that departures may be made therefrom within the scope of the invention, which is therefore not to be limited to the details disclosed herein, but is to be accorded the full scope of the claims.

I claim:

1. A hydraulic grab bucket adapted for use in an earth bore comprising a shell including sides and top and bottom, a jam support element depending from said shell bottom, a drive shaft rotatably mounted on the shell top and having a portion extending into said shell, power means external of said shell rotatively coupled with said drive shaft, hydraulic fluid pump means mounted in said shell and operatively connected to said drive shaft whereby said pump may be actuated to move fluid, a plurality of jaws

pivots mounted on said jaw support element and said jaws being movable between an open and closed position, a piston slidably mounted within said jaw support element below said shell bottom, linking means interconnecting each of said jaws and said piston, a spring biasing said piston toward said shell whereby said jaws will be biased in an open position, a hydraulic ram engaging said piston, fluid conduit means interconnecting said pump and said ram, said ram operatively associated with said pump by fluid through said conduit means whereby said ram may be advanced to overcome said spring biasing and said jaws moved to a closed position, and valve means in said conduit means to release said fluid whereby said jaws may return to said open position.

2. A hydraulic grab bucket as defined in claim 1 wherein said power means, said drive shaft and said hydraulic fluid pump all have a common axis.

3. A hydraulic grab bucket as defined in claim 1 wherein a flexible coupling connects said drive shaft and said hydraulic fluid pump means.

4. A hydraulic grab bucket comprising a shell including sides and top and bottom, a jaw support element secured to said shell bottom, a drive shaft means rotatably mounted in the top of said shell and having a portion extending into said shell, said shaft adapted to be rotated by power means external of said shell rotatably coupled with said drive shaft, hydraulic pump means mounted in said shell, said hydraulic pump means being operatively connected to said drive shaft means, hydraulic ram means mounted on said jaw support element, a plurality of jaws pivotally mounted on said jaw support element whereby said jaws are movable between an open position and a closed position, fluid conduit means connecting said hydraulic pump means and said hydraulic ram means, and mechanical connection between said hydraulic ram means and said jaws whereby said jaws may be moved.

5. The combination of: a drilling rig in which said rig comprises a platform, motor means on said platform, a boom mounted on said platform, a kelly bar suspended from said boom and rotary means on said platform connected to said motor means to rotate said kelly bar, a hydraulic grab bucket comprising a shell including sides and top and bottom, a jaw support element depending from said shell bottom, a drive shaft rotatably mounted on the shell top and having a portion extending into said shell, said drive shaft being rotatably coupled with said kelly bar external of said shell, hydraulic fluid pump means mounted in said shell and operatively connected to said drive shaft whereby said pump may be actuated to move fluid, a plurality of jaws pivotally mounted on said jaw support element and said jaws being movable between an open and closed position, a

10

50

piston slidably mounted within said jaw support element below said shell bottom, linking means interconnecting each of said jaws and said piston, a spring biasing said piston toward said shell whereby said jaws will be biased in an open position, a hydraulic ram engaging said piston, fluid conduit means interconnecting said pump and said ram, said ram operatively associated with said pump by fluid through said conduit means whereby said ram may be advanced to overcome said spring biasing and said jaws moved to a closed position, and valve means in said conduit means to release said fluid whereby said jaws may return to said open position.

6. The combination as defined in claim 5 wherein said fluid conduit means includes a reservoir formed within said shell.

7. The combination as defined in claim 6 wherein said fluid conduit means is adapted to cycle fluid from said reservoir through said pump to said hydraulic ram and from said ram back to said reservoir.

8. A hydraulic grab bucket comprising a shell, a drive shaft means rotatably mounted in the shell and adapted to be rotated by power means external of said shell, hydraulic pump means mounted in said shell, said hydraulic pump means being operatively connected to said drive shaft means, a plurality of jaws pivotally carried by said shell whereby said jaws are movable between an open position and a closed position, hydraulic ram means interconnecting said shell and said jaws whereby said jaws may be pivotally moved, and fluid conduit means connecting said hydraulic pump means and said hydraulic ram means.

9. A hydraulic grab bucket as defined in claim 8 wherein said plurality of jaws include two jaws in face-to-face relationship.

10. A hydraulic grab bucket as defined in claim 9 wherein each jaw is interconnected to said shell by a hydraulic ram.
